UNITED STATES PATENT OFFICE.

WILLIAM S. RESER, OF DAYTON, OHIO, ASSIGNOR OF ONE-THIRD TO
CLARENCE E. RAMBY, OF DAYTON, OHIO.

SEWING-MACHINE BEARING.

No. 857,587.

Specification of Letters Patent.

Patented June 18, 1907.

Application filed October 19, 1906. Serial No. 339,666.

To all whom it may concern:

Be it known that I, WILLIAM S. RESER, a citizen of the United States, residing at Dayton, in the county of Montgomery and State of Ohio, have invented certain new and useful Improvements in Sewing-Machine Bearings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to sewing machines and more particularly to the mechanism of a sewing machine which is instrumental in imparting movement to the shuttle.

The object of the invention is to provide 20 means for centering the bearings of the hanger or the shuttle lever and which may be termed a self-centering adjustable anti-friction bearing. Heretofore tapered screws and cones have been used for the bearings of these parts, and owing to the fact that it is impossible to obtain a perfect center and a perfect bearing with such devices, more difficulty has been experienced with sewing machines in constructing these parts than any other parts of the machine; it becoming necessary to constantly repair or change such bearings after the machines have been placed in use in order to have them maintain even an imperfect adjustment. In the case of the 30 invention the hanger will always 35 rest in a true center and a perfect bearing and the wear incidental to continuous movement is reduced to a minimum and can be taken up without necessitating the throwing 40 of the hanger fork or any other part out of alinement.

Preceding a detailed description of the invention, reference is made to the accompanying drawings, of which—
45 Figure 1 is a side elevation of an arm and bed plate of a sewing machine having my perfect self-centering bearing applied. Fig. 2, is an enlarged sectional view of a portion of the arm of a sewing machine showing the hanger supported and my improved bearing. 50 Fig. 3, is a detail view of the hanger showing the upper end thereof. Fig. 4, is a detail

view in section showing the bearing applied to the shuttle lever.

In a detail description of the invention, 55 similar reference characters indicate corresponding parts.

The hanger or lever 1 is inclosed in the upright portion 2 of the machine arm in which the bearing to be described is mounted. The upper end of said hanger terminates in leaves 3 between which the eccentric 4 rotates and imparts oscillating movement to the hanger from the driving shaft 5; these features thus far described are common in 65 sewing machine construction and require no further description. The lever 1, it will be understood has a pendulum movement and its fulcrum is on two balls 6. The hub 7 of said lever is provided with alined recesses 70 8 which extend into the hub a suitable distance so that the contact between said hub and the balls is reduced to a minimum. It is essential that the balls shall not make contact with the entire surface of the recesses 75 8 as in the case of the ordinary ball seat or cup. This is important for the reason that the balls must be held stationary or must not have movement independent of the lever; this is accomplished by a gripping contact 80 between the outer circumferential edges of said recesses and the balls, the major portion of the inclosed surface of the balls being free from metallic contact or free from contact with the hub. The metal of which the 85 lever 1 is constructed is essentially softer than the balls; there is thus presented to said balls a surface more susceptible to wear than are the balls themselves, which are formed of hardened steel. Owing to this difference in 90 the characters of the two metals which are thus brought in contact there is a grip between the outer circumferential edges of the recesses 8 and the balls 6 as before indicated, which compels the lever and the balls to 95 move in unison or together during the oscillation of said lever. The outer sides of the balls engage in a similar manner the circumferential edges of recesses 12 extending into centering screws 9 constructed of hardened steel. These centering screws, owing to their being constructed of metal similar to that of the balls, enable said balls to turn 100 freely in the ends of the screws while moving.

with the lever as before indicated. Regardless of the position of the lever, a true center and a proper bearing are thus maintained between the parts. The centering screws 9 are provided with openings communicating with the recesses 12 and through which oil may be introduced to lubricate the bearings. In Fig. 4, the same idea of means is shown applied to a shuttle lever 14 which is oscillated from the hanger lever 1 through the engagement of said shuttle lever with the hanger lever below the bed plate 15. Projecting from the underside of the bed plate is a bracket 16, the lower arm of which supports a screw 17 which is screwed therethrough and is maintained in position by a jam nut 18; this screw 17 is constructed of hardened steel and provides an inwardly extended recess 12, with the outer circumferential edge of which, the ball comes in contact. The upper ball support 19 in this adaptation of the device has a fixed connection with the bed plate 15 and a similar recess 12 extending inwardly from the ball, the outer circumferential edge of said recess alone making contact with the ball. The hub 20 of the shuttle lever is suitably recessed as at 8 on each side to permit of the inner sides of the balls being engaged only by the circumferential edges of said recesses. Any undesirable looseness of the bearings may be taken up in either case by a slight adjustment of the centering screws 9 and 17 without changing the centers of said bearings.

Heretofore, much difficulty has been experienced in grinding or preparing the working surfaces of the hanger leaves 3 for contact with the eccentric 4, and in many instances these engaging surfaces are not true; as a consequence, the eccentric imparts to the hanger or lever 1 an uneven movement. This difficulty is quite overcome by the present invention which enables the hanger to be first properly centered between the two balls

before placing it in the machine, to determine the exact point of contact between the eccentric and the leaves; and further, much difficulty has been experienced in locating the openings in the machine arm 2 for the centering screws, it being very difficult to make these openings in exact alinement. As a consequence, the centering screws themselves will often be out of alinement and will cause the trouble and annoyance of an imperfect bearing. By the use of the devices herein shown and described, these difficulties are obviated and a perfect bearing and centering means regardless of any variation in the positions of the centering screws or the hanger recesses, is obtainable.

I claim:

1. In a bearing of the type specified, a lever, said lever having recesses on opposite sides of its fulcrum point, a centering screw on each side of said lever in alinement with said fulcrum point, said centering screws having recesses, and a ball between each centering screw and the adjacent portion of the lever, said balls being engaged on their opposite sides by the circumferential edges of the recesses in said centering screws and said lever, the portions of said balls lying within the circumferences of said recesses being free from contact with the screws or the lever.

2. In a bearing of the type specified, a lever, a centering screw on each side of said lever, a ball interposed between each of said centering screws and the lever and forming the fulcrum of the lever, said balls each engaging on one side the annular rim only of a recess and having the portion of their surface lying within the circumference of said rim free from metallic contact.

In testimony whereof I affix my signature, in presence of two witnesses.

WILLIAM S. RESER.
